UNITED STATES PATENT OFFICE.

HENRY A. MUCKLE, OF ST. PAUL, MINNESOTA.

DESIGN FOR A VEHICLE-SPRING.

SPECIFICATION forming part of Design No. 29,418, dated September 27, 1898.

Application filed July 12, 1898. Serial No. 685,790. Term of patent 14 years.

To all whom it may concern:

Be it known that I, HENRY A. MUCKLE, a citizen of the United States, residing at St. Paul, in the county of Ramsey and State of Minnesota, have invented and produced a new and original Design for a Vehicle-Spring, of which the following is a specification.

My present invention pertains to a new and original design for a vehicle-spring, as will hereinafter be more particularly pointed out, reference being had to the annexed drawing, wherein the spring is shown in perspective.

As illustrated, the leading and material features of my design consist of the central flat or straight section A, from which extend the straight and downwardly-inclined arms B B at each end thereof, and the cyma-recta sections C C, which also extend from the central section A, said cyma-recta sections C C extending out over and in line with the inclined arms B, clips F F securing the mem-

bers together, forming one integral spring or product.

The ends of the arms or sections B are formed with eyes D, and the ends of the cyma-recta sections C are likewise provided with eyes E, though, as before stated, the essential features of my design consist of the section A, the arms or members B B, and the cyma-recta sections C C, all fixedly clipped together as one integral spring or product.

Having thus described my invention, what I claim as new, and desire to secure by Letters Patent, is—

The design for a vehicle-spring, as herein shown and described.

In witness whereof I hereunto set my hand in the presence of two witnesses.

HENRY A. MUCKLE.
